WRAPPING ROLL FOR BENDING MACHINES

William E. Kane, Syracuse, N. Y., assignor to
Kane & Roach, Inc., Syracuse, N. Y., a corpora-
tion of New York

Application June 6, 1940, Serial No. 339,085

13 Claims. (Cl. 153—54)

My invention is directed to a new type of wrapping roll for metal bending machines of the type adapted for bending rods, bars, and structural shapes such as angles, channels, etc., into arcs, circles, and helixes. Although I have developed my invention with special reference to this type of heavy metal bending machine, it is obvious that a hollow roll would likewise be useful in sheet metal bending machines.

In the ordinary shop, the pyramid type bending machine is preferred as this type of machine is readily adaptable for bending material to different radii. It has, however, many disadvantages. The pyramid bender ordinarily includes two rolls fixed in relation to each other and a third roll which may be moved toward and away from the fixed rolls. By adjusting the distance of the movable roll to the fixed rolls, material can be bent to different radii. The three rolls are ordinarily of the same size and are geared together so that the three rolls have the same surface speed. As the rolls are ordinarily of comparatively small diameter, the bending is accomplished by exerting pressure at three points against the material that is being formed. As a result, at the beginning of the bend a flat section will be produced. Likewise, as the end of the material passes through the three rolls, there will be a similar flat section. The result is that true circles or complete arcs cannot be produced by the pyramid machine. It therefore becomes necessary either to curve the flat sections in a supplementary operation or to cut them off.

There are two general types of pyramid benders. In one type, the adjustable roll is carried on a swing arm. In the swing arm type of pyramid bending machine, there is only one position of the swing arm where the center of the adjustable roll is equidistant from the centers of the two fixed rolls. As the swing arm is moved from this position to produce bends of different radii, the adjustable roll will be nearer one of the fixed rolls than to the other. In the second type of pyramid bending machine, the adjustable roll is carried on sliding ways in order that the center of the adjustable roll will always be equidistant from the centers of the fixed rolls no matter to what position the adjustable roll is moved. If it is attempted to convert the pyramid bender to a wrapping machine by substituting a wrapping roll for the adjustable roll, it becomes necessary to change the gearing connecting the adjustable roll to the fixed rolls in order that the surface speed of the adjustable roll and the fixed rolls may be the same. This is im-

practical in the swing arm pyramid type bender. If such adjustment is not made, the surface of the work will be scuffed because of the different surface speeds of the rolls. Furthermore, if the pyramid bender be of the swing arm type, the use of a wrapping roll on the adjustable arm would be objectionable because with wrapping rolls of different diameters the center of the wrapping roll will be closer to one of the fixed rolls than to the other roll, with the result that the bending arc of the wrapping roll would be decreased and much of its usefulness destroyed.

In order to overcome this difficulty and to produce an arc having a uniform bend throughout its length or to produce a true circle, another type of machine is used which is known to those skilled in the art as a wrapping type machine. A wrapping type machine ordinarily includes two rolls fixed with relation to each other and a third movable spindle which may be moved toward and away from the first two rolls. The third roll is carried by the movable spindle. To produce complete true circles, the third roll is made having a diameter somewhat approximating the diameter of the finished work. In the ordinary case, the diameter of the third roll will be smaller than the diameter of the finished work because the metal tends to spring back somewhat after being bent. However, the wrapping machine has the advantage that instead of having only three points of bearing against the work, the work is pressed against the wrapping roll for a distance which is approximately the length of the arc bounded by a center line drawn from the center of one of the fixed rolls to the center of the wrapping roll on one side, and a center line drawn from the center of the second fixed roll to the center of the wrapping roll. It is thus seen that the material is bent against the surface of the wrapping roll through the length of this arc. The result is that the finished article is given a uniform bend throughout its length and comparatively true circles may be produced.

There are two types of wrapping machines made. In the first type, the two fixed rolls are power-driven and the wrapping roll is an idler. This type of machine is suitable for a wide variety of work but where the bend is of a comparatively short radius and the material to be formed is heavy, there may not be sufficient frictional drive positively to force the material through the rolls, with the result that excessive slippage occurs and the surface of the material being formed may be badly scuffed. To overcome this difficulty, the second type of wrapping

machine provides power drive to the three rolls including the wrapping roll. However, when work of different diameters is to be finished, it is necessary to use different diameter wrapping rolls. This requires a change gear system in order that the surface speed of the wrapping roll may approximate the surface speed of the two fixed rolls. In any case, the capacity of the wrapping type machine is limited to the largest size of wrapping roll that may be mounted in the machine and this in turn is limited by the length of the sliding ways.

There is a third type of bending machine in use which is sometimes designated as a four roll pinch bender. This machine has two opposed driving rolls between which material to be formed is fed. On either side of the driving rolls are two idler rolls which are adjustable. The arrangement of the rolls is roughly diamond-shaped—the two pinch rolls on opposite points of the diamond and the two idler rolls being at the other two points of the diamond. The pinch type machine gives a more positive drive to the material than does the wrapping machine having an idler roll, but is subject to the similar limitations as to bending as is the pyramid type machine.

The main object of my invention is to provide a new type of roll which may be used on any of the types of bending machines heretofore described.

Another object of my invention is to provide a hollow roll which may be used on a pyramid or pinch type bending machine to convert the machine into a wrapping type machine.

Another object of my invention is to provide a hollow roll for a pyramid bending machine of the swing arm type, which roll is self-centering.

Another object of my invention is to provide a hollow roll for a wrapping type bending machine, which roll will maintain correct surface speed without the necessity of changing gears.

Still another object of my invention is to provide a hollow wrapping roll for a bending machine, which roll can be made of any desired diameter without regard to the ordinary capacity of the machine.

A still further object of my invention is to provide a hollow wrapping roll for use on a bending machine, which roll can be produced cheaply.

Another object of my invention is to provide a hollow wrapping roll for a bending machine, which roll will be of a minimum weight.

Other objects and advantages of my invention will appear from the following specification and drawings, in which:

Figure 1 is a plan view of a swing arm type pyramid bending machine having vertical spindles and showing the wrapping roll of my invention in use, with the upper shroud plate removed for clarity.

Figure 2 is a diagram of the gearing for driving the three rolls of the bending machine shown in Figure 1.

Figure 3 is a section, parts being broken away, taken on the line 3—3 of Figure 1.

Figure 4 is an exploded perspective view of the hollow roll of my invention showing the shroud plates.

Figure 5 is an elevation, parts being broken away, of a wrapping type bending machine showing the use of my hollow wrapping roll, with the shroud plate carried by a fixed roll.

Figure 6 is a diagram showing the driving gearing of the wrapping machine shown in Figure 5.

Figure 7 is an elevation of a pinch type bending machine, parts being broken away, showing the use of the hollow wrapping roll of my invention.

5 Figure 8 is a section, parts being broken away, taken on the line 8—8 of Figure 5.

Referring now more particularly to Figure 1, the pyramid bending machine comprises a frame 10 in which are journaled the vertical shafts 11 and 12. The shafts 11 and 12 carry the rolls 13 and 14, respectively, which are constructed to rotate with the shafts by means of the keys 15 and 16. A swing arm 17 is pivoted to the frame 10 by means of the shaft 18 so that the swing arm moves in a horizontal plane. Adjustment of the swing arm 17 is made by means of the screw 19 and nut 20. One end of the screw 19 is pivotally secured to the frame 10. The screw projects through a suitable aperture 21 provided adjacent the end of the arm 17 so that when the nut 20 is turned the swing arm may be drawn in toward the axis of the rolls 13 and 14. The shaft 25 is rotatably mounted in the swing arm 17 and carries the roll 26 which is constrained to rotate with the shaft 25 by means of the key 27. Shafts 11, 12 and 25 are geared together by means of the train of gears shown in Figure 2. Power means (not shown) is connected to and drives the gear train. The gears are selected so that the shafts 11, 12 and 25 rotate at the same speed.

30 The hollow wrapping roll of my invention comprises a cylindrical shell 30 which may be slipped over the roll 26. In order that the roll 30 may be restrained from axial movement with reference to the shaft 25, two shroud plates 31 and 32 are provided. In adapting the pyramid bending machine to use my hollow wrapping roll, the roll 26 is removed, lower shroud plate 31 is slipped over the shaft 25, the roll 26 is then replaced and the hollow roll 30 is placed over the roll 26 resting on the shroud plate 31. Shroud plate 32 is then placed on the shaft 25 and the whole assembly secured by means of the nut 33 which is screwed 35 on a threaded upper portion 34 of the shaft 25. Clearance is provided between the shroud plates 31 and 32 and the hollow roll 30 so that the roll 30 is free to move independently of the shroud plates. The hollow roll 30 is made with an outer diameter suitable for the work to be formed. Swing arm 17 is adjusted by means of the nut 20 and the work 35 is fed between the hollow roll 30 and the fixed rolls 13 and 14. Work 35 is thus bent around the wrapping roll 30 in the same 40 manner as in a standard wrapping bending machine.

45 As the roll 26 is driven by the shaft 25, the roll 26 in contact with the inner surface of the shell 30 will act as a friction driver to rotate the hollow roll 30. Thus, with the use of a hollow roll placed over the roll 26, due to the internal friction drive of the roll 26 against the inner surface of the roll 30, the machine is adapted to bend heavier material to smaller radii than is a standard wrapping machine having an idler wrapping roll. Furthermore, it is to be noted that since the hollow roll 30 is free to move eccentrically with relation to the shaft 25 and the roll 26, the roll will automatically align itself with reference to the shafts 11 and 12 regardless of the position of the swing arm 17. If the roll 26 is of the same diameter as the rolls 13 and 14, it is obvious that the outer surface of the hollow roll 30 would have a higher surface speed than either the rolls 13, 14 or 26. 50 As a result, there will be some slip in running

material through the machine. However, this slip is small and can be determined by the ratio of the inside and outside diameter of the hollow roll 30. In rolling material, the slip is distributed between the surface of the roll 26, the inner surface of the roll 30, the outer surface of the roll 30, the work, the work and the rolls 13 and 14. In the ordinary case, the thickness of the shell 30 is small with reference to its diameter. For example, where the outer diameter of the roll is 20 inches, the thickness of the roll will probably not exceed one inch. Hence, the outer surface speed of the roll 30 would be 20% or 1% of the surface speed of the roll 26, assuming for the moment there is no slip between the roll 26 and the inner surface of the hollow roll 30. It is obvious then that there is approximately 11% difference in surface speed to be accounted for. This will distribute itself through slip between the three surfaces mentioned above. By using a roll 26 which is smaller than the rolls 13 and 14, the outer surface speed of the roll 30 may be made equal to the surface speeds of the rolls 13 and 14. The diameter of the roll 26 for a condition of no slip-page can be determined as follows:

The diameters of the fixed rolls 13 and 14 are the same and thus may be indicated as D₁. The diameter of the roll 26 which we are seeking to determine may be represented by D_x. The outside and inside diameters of the wrapping roll are known; therefore, designate the outside diameter as D₄ and the inside diameter as D₃. Then

$$\frac{D_x}{D_1} = \frac{D_3}{D_4}$$

If the work to be formed is of substantial thickness, it may be desirable to take this into account in calculating the diameter D_x. If the thickness of the work is represented by T, then, in the formula, D₄ will equal the outside diameter of the hollow roll plus twice the thickness T of the material.

It is evident that my hollow wrapping roll may be used to bend arcs or circles of very large diameters on a bending machine which would not otherwise have sufficient capacity, since the hollow roll can be of any diameter without being limited by the capacity of the machine to accommodate a roll centered on the shaft 25. The shroud plates 31 and 32 need not be as large as the hollow roll 30 since their function is merely to support and guide the hollow roll 30 while the roll 30 is free to move normal to the axis of shaft 25 without regard to the shroud plates. It is likewise obvious that since the sole function of the shroud plates is to constrain axial movement of the hollow roll, the shroud plates could be mounted on either of the fixed roll shafts 11 or 12.

My hollow wrapping roll is likewise suitable for use on a standard wrapping machine, as shown in Figure 5, wherein the shafts 40, 41 and 42 are positively driven through the gear train as diagrammatically shown in Figure 6. The fixed rolls 43 and 44 of the wrapping machine are of the same diameter. 45 is an ordinary wrapping roll which is concentric with the shaft 42. The gearing shown in Figure 6 is proportioned to drive the rolls 43, 44 and 45 at substantially the same surface speed. By using my hollow wrapping roll, as shown at 47, work of larger diameter than the wrapping roll 45 can be produced in the machine without changing the gear 48 in the gear train shown in Figure 6.

The considerations of slip will be the same as discussed for the pyramid bender and either the

roll 45 may be selected of a proper diameter to give a condition of no slip between the hollow roll 47 and the rolls 43 and 44, or the slip will distribute itself between the roll 45, the inner surface of hollow roll 47, the outer surface of roll 47, the work W, and the work W and rolls 43 and 44.

It is theoretically possible to substitute a pinion gear for roll 26 and provide the roll 30 with internal gear teeth to obtain a positive drive of the wrapping roll. Because of obvious difficulties in maintaining such gear teeth in mesh, the more practical scheme is to employ friction surfaces as I have shown in the drawings.

The machine shown in Figure 5 is a horizontal spindle machine. The shaft 42 is carried on a slide 50 which may be raised or lowered by suitable means, here illustrated as the screw 51. As the hollow roll 47 will rest on the rolls 43 and 44, I have provided a carrier 52 to lift the hollow roll 47 with the slide 50. It is obvious that some such carrier, as 52, would be desirable in any type of horizontal spindle machine to prevent the hollow roll from dropping down on the lower roll or rolls when feeding work into the machine.

In Figure 5 I have shown the shroud plate 49 mounted on the fixed roll shaft 40 to illustrate the flexibility of arrangement which my invention permits.

In Figure 7 I have shown my hollow roll 55 used similarly on a pinch type bending machine. Figure 7 illustrates the use of a large roll 55 with a shroud plate 56 of smaller diameter than the hollow roll 55.

The hollow roll of my invention can be made at a minimum cost as it requires a minimum of material, the thickness of the wall of the hollow cylinder being governed solely by strength requirements which are governed by the weight of the material to be formed.

Although I have shown and described a specific embodiment of my hollow roll for use on bending machines, it is obvious that various changes could be made in its form and proportions, which changes would be well within the skill of the ordinary mechanic and yet would be embraced by the spirit of my invention. I therefore wish to be limited only by the scope of the appended claims.

I claim:

1. A wrapping roll for a bending machine of the type having a plurality of work engaging rolls mounted on substantially parallel roll shafts at least some of which are drive shafts, said wrapping roll comprising a hollow roll adapted to be loosely mounted on one of said shafts, said hollow roll having an outer surface defined as a surface of revolution and adapted for forming the work in cooperation with the other work engaging rolls, and having an internal bearing surface adapted to engage said shaft throughout the work forming operation.

2. A wrapping roll for a bending machine of the type having a plurality of work engaging rolls mounted on substantially parallel roll shafts at least some of which are drive shafts, said wrapping roll comprising a hollow roll adapted to be loosely mounted on one of said drive shafts, said hollow roll having an outer surface defined as a surface of revolution and adapted for forming the work in cooperation with the other work engaging rolls, and having an internal surface adapted to engage the outer surface of said drive shaft to be driven thereby throughout the work forming operation.

3. A wrapping roll for a bending machine hav-

ing a power driven rotating member, said roll comprising a hollow member having an internal cylindrical bearing surface adapted to be frictionally driven by said rotating member, said internal surface having a greater diameter than said rotating member, and said roll having an external work surface comprising a surface of revolution generated about substantially the same axis as the axis of said internal bearing surface.

4. A wrapping roll for a bending machine having a plurality of work engaging rolls and a driving member, comprising a hollow roll loosely mounted on said driving member, said hollow roll having an external work surface comprising a surface of revolution about which said work is formed and an internal cylindrical bearing surface adapted to be frictionally engaged by said driving member, and means for constraining axial movement of said roll.

5. A conversion attachment for converting into a wrapping type bending machine a pyramid bending machine or a pinch bending machine having a plurality of work engaging rolls mounted on substantially parallel roll shafts at least some of which are drive shafts, comprising a hollow wrapping roll adapted to be loosely mounted on one of the driving rolls, said hollow roll having an outer surface defined as a surface of revolution and adapted for forming the work in cooperation with the other work engaging rolls, and having an internal surface adapted to engage the outer surface of said driving roll to be frictionally driven thereby throughout the work forming operation.

6. A conversion attachment for a pyramid type bending machine having a plurality of cooperating metal bending rolls including a driving roll, comprising a hollow cylindrical member loosely mounted on said driving roll and adapted to be internally driven by said roll, said member having an external surface adapted to engage the metal to be bent, and means to retain said hollow member against substantial axial movement thereof.

7. A conversion attachment for a four roll pinch type bending machine having two driving rolls, comprising a hollow cylindrical member loosely mounted on one of said driving rolls and adapted to be internally driven thereby, and means to retain said hollow member against substantial axial movement thereof.

8. In a bending machine of the type having a plurality of work engaging rolls mounted on substantially parallel roll shafts at least some of which are drive shafts, in combination, a hollow roll having an external working surface defined as a surface of revolution and adapted for forming the work in cooperation with the other work engaging rolls, and having an internal bearing surface, said hollow roll being loosely mounted on one of said shafts and being maintained in contact therewith during the work forming

operation by the pressure of said other cooperating rolls.

9. In a bending machine of the type having a plurality of work engaging rolls mounted on substantially parallel roll shafts at least some of which are drive shafts, in combination, a hollow roll having an external working surface defined as a surface of revolution and adapted for forming the work in cooperation with the other work engaging rolls, and having an internal bearing surface, said hollow roll being loosely mounted on one of said drive shafts and being maintained in substantially line driving contact therewith during the work forming operation by the pressure of said other cooperating rolls.

10. In a bending machine of the type having a plurality of work engaging rolls mounted on substantially parallel roll shafts at least some of which are drive shafts, in combination, a hollow roll having an external working surface defined as a surface of revolution and adapted for forming the work in cooperation with the other work engaging rolls, and having an internal bearing surface, said hollow roll being loosely mounted on one of said shafts and being maintained in contact therewith during the work forming operation by the pressure of said other cooperating rolls, and means to retain said hollow roll against substantial axial movement.

11. In a bending machine having a plurality of work engaging rolls and a shaft, in combination, a hollow roll loosely mounted on said shaft, said hollow roll having an outer surface defined as a surface of revolution and adapted for forming said work in cooperation with said other rolls, an internal cylindrical bearing surface adapted to engage said shaft, and guide means for constraining axial movement of said roll.

12. In a pyramid bending machine having two fixed driving rolls, a movable driven spindle, and a third driving roll mounted on said movable spindle, in combination, a shroud plate carried by said movable spindle mounted at one end of said third driving roll, a second shroud plate carried by said movable spindle and mounted at the other end of said third driving roll, and a hollow roll loosely mounted between said shroud plates and encircling said third driving roll.

13. In a bending machine of the class described, having a frame, at least one rotating member mounted on said frame, a slide mounted on said frame adapted for movement towards and away from said rotating member, a second rotating member mounted on said slide, and means for moving said slide, in combination, a hollow roll adapted to be loosely mounted on said second rotating member, and means independent of said second rotating member carried by said slide for supporting said hollow roll when said slide is moved away from said first rotating member.

WILLIAM E. KANE.
